(57) **CLAIM**

I claim the ornamental design for a fire suppression system bracket, as shown and described.

DESCRIPTION

FIG. 1 is a top front perspective view of a fire suppression system bracket showing my new design;

FIG. 2 is a top view of the device shown in FIG. 1;

FIG. 3 is a bottom view of the device shown in FIG. 1;

FIG. 4 is a front view of the device shown in FIG. 1;

FIG. 5 is a rear view of the device shown in FIG. 1;

FIG. 6 is a first side view of the device shown in FIG. 1; and,

FIG. 7 is a second side view of the device shown in FIG. 1.
